UNITED STATES PATENT OFFICE.

DAVID E. ROWLAND, OF CANTON, OHIO.

HOIST.

SPECIFICATION forming part of Letters Patent No. 690,774, dated January 7, 1902.

Application filed July 30, 1900. Serial No. 25,238. (No model.)

To all whom it may concern:

Be it known that I, DAVID E. ROWLAND, a citizen of the United States, residing at Canton, in the county of Stark and State of Ohio, have invented certain new and useful Improvements in Hoists; and I do hereby declare that the following is a full, clear, and exact description of the same, reference being had to the annexed drawings, making a part of this specification, and to the figures of reference marked thereon, in which—

Figure 1 is a perspective view showing the different parts properly assembled. Fig. 2 is a side elevation of the hoist-head, showing 15 an edge view of the pulleys. Fig. 3 is a vertical section of the hoist-head and its different parts on a line with the pulley-axle, except the axle is not shown in section. Fig. 4 is a detached view of the supporting-hook. 20 Fig. 5 is a detached view of the hook-connecting head or flanged collar. Fig. 6 is a detached view of the hook-connecting-head sections. Fig. 7 is a detached view of the collar-shifting yoke and lever. Fig. 8 is a 25 detached view of the sliding collar and its pins. Figs. 9 and 10 are detached views of the larger hoist-pulleys. Figs. 11 and 12 are detached views of the smaller hoist-pulleys.

The present invention has relation to 30 hoists; and it consists in the different parts and combination of parts hereinafter described, and particularly pointed out in the claims.

Similar numerals of reference indicate 35 corresponding parts in all the figures of the drawings.

In the accompanying drawings, 1 represents the hoist block or head, the upper end of which is yoke-shaped and the lower end or 40 portion provided with the chain-guides 2, said chain-guides being located and arranged substantially as shown in Fig. 1.

To the head or frame 1 is connected the pulley-shaft 3, and upon which pulley-shaft 45 are mounted the pulleys 4 and 5, said pulleys being located side by side, as illustrated in Figs. 1, 2, and 3. The pulley 4 is somewhat larger in diameter than the pulley 5, said pulleys being so formed for the purpose 50 of imparting a differentiated movement to the different members of the endless chain 6, said endless chain being located and arranged

substantially as shown, and, as shown, the members are located over the pulleys 4 and 5 and two members thereof located under the 55 pulley 7, which pulley is properly journaled to the elevating head or block 8, said head or block being provided with the ordinary connecting-hook 9 or its equivalent.

It will be understood that by forming the 60 pulleys 4 and 5 of different diameters and moving the elevating-chain over said pulleys in the direction to elevate the hoist head or block 8 a slow upward movement will be imparted to the head 8, together with the load 65 connected thereto, thereby providing a means for easily elevating by hand heavy articles.

By my peculiar arrangement I am enabled to lower the elevating-head after it has been carried to the desired height without locking 70 the elevating-chain backward.

For the purpose of overcoming the slow manner of lowering the elevating-head 8, as above described, I employ the single pulleys 4 and 5 and locate them side by side and 75 mount them upon the shaft 3, and for the purpose of causing the pulleys 4 and 5 to rotate in unison when it is desired to have them so rotated the sliding pins 10 are provided, which sliding pins are located in the apertures 11, being formed through the pulley 4, and the pins extended into the apertures 12, formed in the pulley 5, when they register with the pins 10, or, in other words, said pins enter the apertures 12 at the time they register with the apertures 11, thereby rotatably 85 connecting the pulleys 4 and 5 together. When it is desired to have the pulleys 4 and 5 rotated independently upon the shaft 3, the lever 13 is pulled downward at its outer end 90 by means of the chain or cord 14, said chain or cord being extended downward to a point where it can be conveniently reached by the hand of an operator. As the outer end of the lever 13 is moved downward the bottom 95 or lower end of the yoke 15 will be moved laterally and away from the outer face of the pulley 4 and carry with it the grooved collar 16, to which grooved collar the pins 10 are securely attached, and as the grooved collar 100 16 is moved away from the pulley 4 it will carry with it the pins 10, thereby disconnecting said pins from the apertures 12, at which time the pulleys 4 and 5 are free to rotate in-

dependently of each other. It will be understood that the grooved collar 16 rotates at all times with the pulley 4, inasmuch as the pins 10 are never disconnected from the pulley 4.

5 For the purpose of providing for the sliding movement of the grooved collar 16 the pulley 4 is provided with the hub 17, which hub is formed of such a length that the grooved collar 16 can move back and forth 10 or to and from the outer face of the pulley 4. For the purpose of reducing the friction of the grooved collar 16 and at the same time carrying said collar the outer portion of the hub 17 is provided with the fins or ribs 18, and 15 upon which ribs or fins the collar rests or moves. It will be understood that the ribs or fins should be so formed that they will engage the inner periphery of the aperture formed in the sliding collar, thereby allowing 20 a free movement back and forth upon the hub proper.

The pulley 4 is provided with a chamber 19, which chamber is for the purpose of holding the antifriction-rollers 20, said antifriction-rollers being located and arranged substantially as shown in the drawings. The pulley 5 is provided with the hub 21, and said pulley is also provided with the chamber 22, which chamber is for the purpose of receiving the 30 antifriction-rollers 23, said rollers being located and arranged substantially as shown in the drawings.

The top or upper end of the hoist frame or head 1 is provided with the recess or chamber 23^a and into which chamber or recess are placed the coupling-head members 24, which coupling-head members are each provided with the semicircular groove 25, and when said members are placed together the grooves 40 25 will form a complete circle, which grooved circle is for the purpose of receiving the flange 26, formed upon the lower end of the head 27, as illustrated in Fig. 3.

To the head 27 is connected the suspending-hook 28, said suspending-hook being headed at its bottom or lower end, thereby securely connecting the head 27 to the hook 28, and by providing the groove 25 in each member of the coupling-head 24 said coupling-head will be connected to the head 27 by means of the flange 26, thereby producing a swivel connection between the hook 28 and the head or frame 1.

The coupling-head members 24 are each provided with the downward-extending arm 29, to which arms is pivotally connected the lever 13, said lever being also pivoted to the head or frame 1 by means of the rivet or bolt 30 or its equivalent at a point directly over 60 the downward-extending yoke 15.

It will be understood that by providing two pivotal points for the lever 13 when said lever is moved downward at its outer end its inner end will move upward, carrying with it 65 the head 1, and in order to provide for this movement of the head 1 the chamber 23^a is so formed that it will allow the head 1 to come

and go or move in a limited sense up and down upon the members of the coupling-head 24, it being understood that the chamber 23^a 70 will at all times hold the members 24 in proper contact with each other. The only object in making the coupling-head 24 in two separate pieces or halves is to provide a means for connecting said members or head with the head 27. 75

For the purpose of providing a brake for the pulley 5 the lever 13 is provided with the shoe 31, which shoe is preferably formed integral with said lever and is so located that it will engage the periphery of said pulley 5 80 at a time when the lever is moved downward at its outer end. The shoe 31 should be so adjusted that it will stop the downward movement of the lever 13 at a point or time when the pins 10 are disconnected from the pulley 5, thereby allowing the pulley 5 to be held 85 against rotation and allow an independent rotation of the pulley 4.

For the purpose of insuring the engagement of the pins 10 with the apertures 12 the inner 90 face of the pulley 5 is provided with the inclines 32, or, in other words, recesses having inclined seats are provided, said recesses being illustrated in Fig. 11. In the drawings I have illustrated two pins 10, said pins being 95 arranged as shown; but it will be understood that a single pin will bring about the same result as the two pins—that is to say, by the longitudinal movement of a single pin in the same manner that the two pins show the pulleys 4 and 5 can be connected and disconnected 100 rotatably one from the other.

It will be understood that by pivotally connecting the lever 13 to the coupling-head 24 or to the integral arms thereof and also pivotally connecting said lever to the hoist block or frame 1 the weight of said head or frame, together with its different parts, except the coupling-head 24, the flange-head 27, and the hook 28, is utilized, together with the chain 110 and the elevating-head, to force the outer end of the lever 13 upward and at the same time forcing the collar 15 toward the pulley 4, by which arrangement the pulleys 4 and 5 are rotatably connected together by the longitudinal movement of the pin or pins 10. 115

Having fully described my invention, what I claim as new, and desire to secure by Letters Patent, is—

1. In a hoist of the class described, a frame 120 provided with a chamber at its upper portion, a coupling-head located in the chamber, a head journaled to the coupling-head, a lever pivotally connected to the coupling-head and to the frame, a downward-extending yoke, a 125 sliding collar operatively connected to the yoke and provided with a pin, a hub carrying the sliding collar, pulleys mounted upon the shaft and provided with apertures to engage the pin of the sliding collar, an elevating pulley-block and an endless chain, all arranged substantially as and for the purpose specified. 130

2. In a hoist a frame, means for suspending the frame, a shaft carried by the frame, a

coupling-head, a lever pivoted to the coupling-head and to the frame, said lever provided with a brake-shoe, pulleys mounted upon the shaft carried by the frame and means for disconnecting and connecting the pulleys and an elevating-chain, all arranged substantially as and for the purpose specified.

3. In a hoist of the class described, a frame, pulleys carried by the frame, a coupling-head connected to the frame, a flanged head connected to the coupling-head, a hook connected to the flanged head, a lever pivotally con-

nected to the frame and to the coupling-head and an elevating-chain, and an elevating-block, substantially as and for the purpose specified.

In testimony that I claim the above I have hereunto subscribed my name in the presence of two witnesses.

DAVID E. ROWLAND.
